OIL BURNER

Oscar C. Schroeder and Stanley Perry, Chicago,
Ill.; said Perry assignor to Automatic Burner
Corporation, Chicago, Ill., a corporation of
Illinois

Application January 2, 1932. Serial No. 584,539

13 Claims. (Cl. 158—77)

Our invention relates to oil burners of the type comprising a rotating atomizer in the form of a cup member operating to discharge from its upper edge in finely divided condition, oil supplied thereto and means for causing atomizing air to flow in a direction outwardly of the cup member into contact with the air, the air commonly flowing upwardly through the cup member and being directed outwardly to the oil.

As structures of this general character have hitherto been provided the air currents referred to contact with the oil throughout at least the greater part of the travel of the oil upwardly along the inside surface of the cup member and thus where the air contains dust or other particles, these particles, wetted by the oil, accumulate on the side wall of the cup member and on the structure commonly provided adjacent the upper edge of the cup member for directing the oil and air outwardly from the cup member, requiring the cleaning of these parts from time to time to insure the most efficient operation of the burner.

Our object, generally stated, is to provide a construction of the general type above referred to, whereby accumulation on the cup member or adjacent parts, of dirt or other foreign particles, entrained with the air supplied to the oil, will be prevented.

Referring to the accompanying drawings:

Figure 1 is a broken view in vertical sectional elevation of an oil burner constructed in accordance with our invention.

Figure 2 is a broken enlarged view in sectional elevation of a detail of the construction showing the way in which our improvement operates.

Figure 3 is a plan view of the uppermost, deflector, member of the burner.

Figure 4 is a plan view of a member of general frusto conical shape serving as a means for maintaining separate the streams of oil and air until the oil has reached a certain position; and

Figure 5, a section taken at the line 5 on Fig. 4 and viewed in the direction of the arrow.

Referring to the particular construction shown and in connection with which we have chosen to illustrate our invention, and which as to its general features of construction is the same as that shown in the pending application for United States Letters Patent filed by Stanley Perry, Serial No. 516,186, filed February 16, 1931, it represents the bottom of the combustion chamber 2 of a furnace and formed of a plate 3 having a covering of refractory material, the plate 3 contain-

ing an aperture 4 in which a neck-ring 5 having an outwardly extending flange 5^a is confined.

The construction also comprises a vertically disposed electric motor represented at 6, the upper end of the armature shaft 7 of which is provided with a circular cup member 8 containing a large central opening 9 in its bottom which is upwardly deflected as shown to provide an annular trough 10, a circular deflector plate 11 extending above the cup member 8 in spaced relation thereto and provided with a set of vanes 12 depending into the cup member 8, and means hereinafter described and represented generally at 13 for maintaining separate the oil and air supplied to the member 8 until the oil has reached a certain point as hereinafter described.

The deflector plate 11 is secured to the upper end of the shaft 7 by a nut 14 clamping the plate 11 between it and the annular flange 15^a of a sleeve 15 surrounding the shaft 7 and bearing at its lower end against a stop 16 on the latter, with a ring 17 interposed between the flange 15 and the plate 11. The ring 17 is provided with radial fingers 18 which extend between certain of the vanes 12 and are provided with depending extensions 19 secured to the inner side of the member 8 for supporting the latter on the shaft 7 whereby the member 8 and the deflector plate 11 rotate with this shaft.

The member 8 is preferably of the form shown, namely, to provide a lower circular side wall portion 20, an intermediate circular wall portion 21, and an upper circular wall portion 22 outwardly offset from the portion 21 and extending in vertically spaced relation to the marginal edge of the plate 11 which latter is preferably of the form shown to provide an upwardly and outwardly inclined marginal edge portion 23 which extends above the upper portion of the member 8, each wall portion 20, 21 and 22 preferably sloping outwardly in an upward direction.

The construction shown also comprises a set of vanes 24 which extend generally radially of the longitudinal axis of the member 8, these vanes being secured to the outer surface of the member 8 and extending from points substantially coincident with the lower edge of the member 8 to points substantially coincident with the lower extremity of the side wall 21, these vanes being preferably set at a slight angle to the radial plane to present a slight lead as set forth in said pending application.

Surrounding the member 8 in spaced relation thereto is a ring 25 having horizontal flanges 26 and 27 and supported by a series of uprights 25^a 110

(certain thereof only being shown) secured at their lower ends to the upper edge of a supporting structure 100 in which the motor 6 is supported on the spring 101.

5 Resting on the flange 26 and against the flange 27 is a ring 28 provided about its periphery with a series of radially disposed vanes 29 which incline slightly downwardly. The outer marginal edge of the flange 26 is located above the plane of 10 the top of the neck ring 5 and slightly inwardly of this top edge, and the vanes 29 thus project across the space between the rings 5 and 25 as shown.

The means shown for supplying oil to the cup 15 member 8 comprise a pipe 30 leading from any suitable source of oil supplied under moderate pressure or gravity head to the lower end of a passage 31 in a boss 32 forming a part of the structure 100, the upper end of this passage opening 20 into a pipe 33 which discharges at its depending portion 34 into the trough 10.

The arrangement of the parts of the assembly just described is such that oil fed to the trough 10 of the cup member 8 rises upwardly along the 25 inner surface of the annular side wall of the member 8 and discharges therefrom laterally outwardly over, and throughout substantially the entire periphery of, the upper edge of the cup member and thus into the combustion chamber, 30 during the rotation of the armature shaft 7, air being supplied to the oil thus discharging from the cup member, as hereinafter described.

In the particular arrangement shown air for atomizing the oil discharged from the cup member 8 is forced upwardly through the opening in the bottom of the cup member 8 and outwardly in all directions through the space between the upper edge of the cup member 8 and the deflector 11, by the vanes 12 which form a fan device.

40 In the particular arrangement shown provision is made not only for the passage of air upwardly through the cup member 8 as stated above, but also through the space between the ring 25 and the cup member and represented at 35 and 45 through the space over which the vanes 29 extend, air being supplied to the burner through an opening 36 in the top of the supporting structure 100 and also, and preferably, controllably, through the space between the neck ring 5 and the upper portion of the supporting structure 100 and which contains the opening 36.

50 The structure shown also comprises a fan 37 shown as of the propeller type and having blades of either a fixed or adjustable pitch, this shaft being fixed on the armature shaft 7 preferably at the point shown in the drawings within the neck ring 5 and preferably within a ring 38 supported on studs 39 (one only of which is shown) carried by the uprights 25^a, the fan 37 thus being located 55 below the air passage over which the vanes extend, the air passage 35 and the passage through the cup member 8.

The fan 37, in the particular construction shown, operates not only to force air upwardly 60 through the opening in the bottom of the cup member 8, but also to force air outwardly through the passage 35 and the passage over which the vanes 29 extend, the vanes 24 serving to augment the action of the propeller 37 in 65 forcing air through the passage 35 as fully described in our said pending application.

70 Referring now to the means 13 hereinbefore referred to and constituting our present improvement, these means, in accordance with the particular illustrated embodiment of our invention

comprise a member 40 presenting an upper inverted generally frusto conical shaped portion 41 and a skirt portion 42 at the lower constricted end of the portion 41, the lower edge of the member 40 containing slots 43 extending from the lower portion of the frusto conical portion 41 down through the skirt portion 42, the metal at the upper ends of these slots being outwardly deflected as represented at 44 to form seating lugs.

The member 40 fits into the cup member 8 as shown and rests at its seating lugs 44 on the wall portion 21 of the cup member. The external diameter of the skirt portion 42 is slightly less than the internal diameter of the wall portion 20 of the member 8 into which the skirt portion downwardly extends to thereby form an annular passage between the member 40 and the wall 20 to permit of the upward flow of oil along the inside surface of the cup member 8, the slots 43 being provided to receive the depending portions 19 on the fingers 18.

The parts described are so proportioned that the upper edge of the member 40 which preferably terminates in the same horizontal plane as the upper edge of the cup member 8, will be spaced a slight distance from the upper edge of the cup member 8 as shown to provide an annular passage between these parts through which the oil discharges outwardly from the cup member 8.

From the foregoing description it will be understood that the air which enters the opening 9 in the bottom of the cup member 8 and flows upwardly through the latter flows upwardly 11 through the member 40 discharging outwardly from the latter in all radial directions through the annular space between the upper edge of the member 40 and the deflector plate 11 thereabove as will be manifest from an inspection of Fig. 2 11 and thus into contact with the oil discharging upwardly from the cup member 8 with the result of atomizing the oil so discharged. Thus the oil as it flows upwardly along the inner surface of the cup member 8 and the air which flows upwardly through this cup member are maintained separated whereby dust, or other particles, entrained in the air discharge from the burner in dry condition thus avoiding accumulation of the dust, or other particles, on the portions of the 12 burner in contact with which the oil flows, the dirt, or other particles, in the air and discharging from the burner being blown out over the upper edge of the cup member 8 and into the flame.

The member 40 preferably, and as shown, extends downwardly into the cup member 8 to such a distance that little, if any, dust entrained with the air can be picked up by the oil and carried to the upper edge of the cup member 8.

While we have illustrated and described a particular embodiment of our invention, we do not wish to be understood as intending to limit it thereto as the same may be variously modified and altered and the invention embodied in other forms of structure, without departing from the spirit thereof.

What we claim as new, and desire to secure by Letters Patent, is:

1. In an oil burner the combination of a rotary hollow oil spraying member open at its top, the upper edge portion of said member extending upwardly and from which oil supplied to said member discharges, a hollow partition-forming member in said oil spraying member the upper edge of which is of a diameter less than 150

the diameter of the upper edge of said oil spraying member and extends adjacent the upper edge of the latter, a deflector above, and spaced from, said members and operating to deflect air discharged thereto from said second-named member in an outward direction crosswise of the upper edge portion of said oil spraying member for mixture with the oil to produce a saucer-like flame, and means for producing flow of air through the upper end of said second-named member.

2. In an oil burner, the combination of a rotary hollow spraying member open at its top and bottom, the upper edge portion of said member extending upwardly and from which oil supplied to said member discharges, a hollow partition-forming member in said oil spraying member the upper edge of said member being of a diameter less than the diameter of the upper edge of said oil spraying member and extends adjacent the upper edge of the latter, a deflector above, and spaced from, said members and operating to deflect air discharged thereto from said second-named member in an outward direction crosswise of the upper edge portion of said oil spraying member for mixture with the oil to produce a saucer-like flame, and means for producing flow of air through the bottom of said oil spraying member and through said second-named member.

3. In an oil burner the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, a deflector above, and spaced from, said members and operating to deflect air discharged thereto from said second-named member in an outward direction crosswise of the upper edge portion of said oil spraying member for mixture with the oil to produce a saucer-like flame, means for producing flow of air through the upper end of said second-named member, and means for causing air to flow along the exterior surface of said oil spraying member to the oil discharging therefrom, but at a lesser velocity than that of the air discharging from said second-named member.

4. In an oil burner the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, a deflector above, and spaced from, said members and operating to deflect air discharged thereto from said second-named member in an outward direction crosswise of the upper edge portion of said oil spraying member for mixture with the oil to produce a saucer-like flame, and a fan located in said second-named member for causing air to flow through the upper end of the latter and against said deflector.

5. In an oil burner the combination of a rotary hollow oil spraying member open at its top, the upper edge portion of said member extending upwardly and from which oil supplied to said member discharges, a hollow partition-forming

member in said oil spraying member the upper edge of which is of a diameter less than the diameter of the upper edge of said oil spraying member and extends adjacent the upper edge of the latter, a deflector above, and spaced from, said members and operating to deflect air discharged thereto from said second-named member in an outward direction crosswise of the upper edge portion of said oil spraying member for mixture with the oil to produce a saucer-like flame, a fan located in said second-named member for causing air to flow through the upper end of the latter and against said deflector and means for causing air to flow along the exterior surface of said oil spraying member to the oil discharging therefrom, but at a lesser velocity than that of the air discharging from said second-named member.

6. In an oil burner the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, a deflector above, and spaced from, said members and operating to deflect air discharged thereto from said second-named member in an outward direction crosswise of the upper edge portion of said oil spraying member for mixture with the oil to produce a saucer-like flame, a fan located in said second-named member for causing air to flow through the upper end of the latter and against said deflector, and a fan on the exterior surface of said oil spraying member for forcing air along the latter to the oil discharging therefrom, but at a lesser velocity than that of the air discharging from said second-named member.

7. In an oil burner, the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, the upper portion of said second-named member being of inverted frusto conical form, a deflector above, and spaced from, said members, the undersurface of said deflector and the upper surface of said second-named member converging outwardly, said deflector operating to deflect air discharged thereto from said second-named member in a direction crosswise of the upper edge portion of said oil spraying member for mixture with the oil to produce a saucer-like flame, and means for producing flow of air through the upper end of said second-named member.

8. In an oil burner, the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, a deflector above, and spaced from, said members and operating to deflect air discharged thereto from said second-named member.

- ber in an outward direction crosswise of said oil spraying member for mixture with the oil to produce a saucer-like flame, the upper portion of said second-named member being of inverted 5 frusto conical form and the undersurface of said deflector and the upper surface of said second-named member converging outwardly, and means for producing flow of air through the upper end of said second-named member.
- 10 9. In an oil burner, the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, a deflector above, and spaced from, 15 said members and operating to deflect air discharged thereto from said second-named member in an outward direction crosswise of said oil spraying member for mixture with the oil to produce a saucer-like flame, the upper portion of 20 said second-named member being of inverted frusto conical form and the undersurface of said deflector, above said second-named member, inclining upwardly and outwardly, said deflector, undersurface and the upper surface of said second-named member converging outwardly, and means for producing flow of air through the upper 25 end of said second-named member.
- 10 10. In an oil burner the combination of a rotary hollow oil spraying member open at its top, the upper edge portion of said member extending upwardly and from which oil supplied to said member discharges, a hollow partition-forming member in said oil spraying member the upper edge of which is of a diameter less than the diameter of the upper edge of said oil spraying member and extends adjacent the upper edge of the latter, a deflector above, and spaced from, 30 said members and operating to deflect air discharged thereto from said second-named member in an outward direction crosswise of the upper edge portion of said oil spraying member for mixture with the oil to produce a saucer-like flame, and means for producing flow of air into the bottom of said oil spraying member and through said second-named member.
- 10 11. In an oil burner, the combination of a rotary hollow oil spraying member open at its top and bottom, the lower portion of said member being smaller than its top portion and its upper edge extending upwardly and from which oil supplied to said member discharges, a hollow partition-forming member in said oil spraying member and open at its top and bottom, said last-named member having a frusto conical upper end portion and a lower end portion of less diameter than its upper end portion and disposed in 40 said first-named member substantially concentric therewith, the upper edge of said second-named member being of a diameter less than the diameter of the upper edge of said oil spraying member and extending adjacent the upper edge of the latter, a deflector above, and spaced from, 45 said members and operating to deflect the air discharged thereto from said second-named member in an outward direction crosswise of the upper edge portion of said oil spraying member for mixture with the oil to produce a saucer-like flame, and means for producing flow of air through the upper end of said second-named member.
- 10 12. In an oil burner, the combination of a rotary hollow oil spraying member open at its top and bottom, the side wall of said member comprising an upper portion, a lower portion of reduced diameter and an intermediate portion of inverted substantially frusto conical form, the upper edge of said upper portion extending upwardly and from which oil supplied to said member discharges, a hollow partition-forming member in said oil spraying member and open top and bottom, said last-named member having an upper portion of inverted substantially frusto conical form disposed in the upper end of said oil spraying member and a lower reduced portion extending into the lower end of said oil spraying member, the lower end of said second-named member being of a diameter greater than the opening in the bottom of said oil spraying member and the upper edge of said second-named member being of a diameter less than the diameter of the upper edge of said oil spraying member and extending adjacent the upper edge of the latter, a deflector above, and spaced from, 50 said members and operating to deflect the air discharged thereto from said second-named member in an outward direction crosswise of the upper edge portion of said oil spraying member for mixture with the oil to produce a saucer-like flame, and means for producing flow of air into the bottom of said oil spraying member and through said second-named member.
- 10 13. In an oil burner, the combination of a rotary hollow oil spraying member open at its top and bottom, the side wall of said member comprising an upper portion, a lower portion of reduced diameter and an intermediate portion of inverted substantially frusto conical form, the upper edge of said upper portion extending upwardly and from which oil supplied to said member discharges, a hollow partition-forming member in said oil spraying member and open top and bottom, said last-named member having an upper portion of inverted substantially frusto conical form disposed in the upper end of said oil spraying member and a lower reduced portion extending into the lower end of said oil spraying member, the lower end of said second-named member being of a diameter greater than the opening in the bottom of said oil spraying member and the upper edge of said second-named member being of a diameter less than the diameter of the upper edge of said oil spraying member and extending adjacent the upper edge of the latter, a deflector above, and spaced from, 55 said members and operating to deflect the air discharged thereto from said second-named member in an outward direction crosswise of the upper edge portion of said oil spraying member for mixture with the oil to produce a saucer-like flame, and means for producing flow of air through the upper end of said second-named member.
